UNITED STATES PATENT OFFICE.

ROBERT L. BLACK, OF ROANOKE, VIRGINIA.

LUBRICATOR.

Application filed February 9, 1925. Serial No. 7,881.

This invention pertains to lubricators and has among its objects to provide improved means for the lubrication of the flanges on wheels having flanged treads, such as are used on railway locomotives and cars.

It has been found in railway locomotive operation that the wear on the flanges of the wheels and on the side of the rail can be materially reduced by providing a lubricant between the two. Not only does this lubrication increase the amount of service to be secured from both the wheels and the rail, but it also reduces the tendency of the flange to climb the rail on curves and cause a derailment. The reduction in the wear of the wheel flange and the rail, as well as the reduction in the tendency of the flange to climb the rail, has become of great importance, especially where locomotives of maximum weight are operated at high speeds around sharp curves.

There are in use at present, various devices for lubricating the flanges of the wheels in order to accomplish the advantages enumerated above. These, however, on account of the number, and often times intricate, parts of which they consist, are expensive both as to first cost and as to maintenance. Many of them also require considerable attention from the enginemen while the locomotive is in service.

The object of this invention is to provide a lubricator consisting of a few parts of simple design, having a low first cost, automatic in operation and having practically no maintenance expense.

With these objects in view, the invention consists of the formation, combination and arrangement of the parts as set forth, particularly in the appended claims, the various elements being so co-ordinated to produce improvements generally in this art.

In the drawings Fig. 1 is an end elevational view of my lubricator showing how it may be secured to some part of the frame of the locomotive, and also showing its relative position to the flange of the wheel it serves. Fig. 2 is a vertical section taken approximately on line 2—2 of Fig. 1. Fig. 3 is an end elevational view of the lubricator with the means of supporting it removed. Fig. 4 is a side elevational view of Fig. 3. Fig. 5 is a vertical section taken approximately on line 5—5 of Fig. 4. Fig. 5 also shows how the lubricator fits over the flange of the wheel and how the lubricant is fed

from a reservoir in the lubricator to the flange.

Referring to these drawings, which show one embodiment of the invention, the lubricator 1 is supported by the flange 2, which it serves and is held in a comparatively fixed position longitudinally on the flange 2 by means of the bracket 3, which is in turn secured to some convenient part of the locomotive frame 4 by means of bolts 5.

The lubricator 1 is secured to the bracket 3 by means of the bolt 6. The opening 7 in the bracket 3, for the bolt 6, is elongated to allow for vertical movement of the lubricator. When any unevenness of the track is encountered, the wheel will move up or down relative to the frame of the locomotive. The elongated opening 7 in the bracket 3 will permit the lubricator to move with the wheel and to remain always on the flange of the wheel, due to its own weight. The bracket 3 is also constructed so that there is a certain amount of clearance between it and the lubricator as shown at 8. This will permit the lubricator 1 to remain in position on the flange 2 when transverse movement of the wheel takes place, due to lateral clearance between the driving box and the hub of the wheel.

On one side of the lubricator, lugs or ears 9 are provided through which the bolt 6, securing the lubricator to the bracket, passes. On the opposite side of the lubricator, similar lugs or ears 10 are provided through the openings of which a retaining pin 11 is placed. This retaining pin extends under some fixed portion of the frame of the locomotive and prevents the lubricator from being turned over on account of any unevenness in the flange of the wheel. It, therefore, makes no difference in which direction the wheel turns with respect to the lubricator, and if the lubricator should become unseated, it will drop back on its seat on the flange, due to its own weight.

A cover or cap 12 fits over the top of the lubricator and is held in position by means of the keeper 13. A hole 13^a is provided in the top of the cap 12, so that the reservoir of the lubricator may be filled without removing the cap. The keeper 13 is located off the center line of the lubricator, so that in applying the cap the hole 13^a, which is also off the center line of the lubricator, will be on the outside of the flange of the wheel where it is easily accessible for filling.

The Lubricator itself consists of a reservoir 14, from which a lubricant is furnished to the flange of the wheel 2, through an opening 15 in the bottom of the lubricator, by means of capillary attraction through an absorbent material, such as waste 16. A partition 17 is provided between the reservoir 14 and the opening 15, so that none of the lubricant except that which passes through the waste 16 may come in contact with the flange of the wheel. A sufficient quantity of the waste 16 is placed in the lubricator, so that there is no possibility of the lubricant being splashed over the top of the partition 17. The amount of lubricant carried from the reservoir 14 to the flange of the wheel, is sufficient to keep it lubricated, but is not enough so that it will run down on the tread of the wheel and cause the wheel to slip.

While I have shown and described the preferred embodiment of the invention together with certain detailed features as to the construction of the mounting it should be understood that the disclosure is for illustrative purposes only and that the right is reserved to make all such changes in the form and arrangement of parts as will not depart from the spirit of the invention or the scope of the claims hereto appended.

Having thus provided a lubricator consisting of a small number of parts, low first cost and maintenance, automatic in operation, what I claim is:

1. The combination of a wheel having a flanged tread, a lubricator comprising a stationary guide bracket, a reservoir member mounted for vertical and lateral sliding movement within the guide and resting on and supported by the flange of said wheel, said reservoir member having limited rocking movement in the plane of the wheel, means carried by said reservoir member for limiting its rocking movement, and lubricating means within the reservoir.

2. The combination of a wheel having a flanged tread, a stationary frame element spaced from the wheel, a guide bracket structure carried by said stationary frame element, a reservoir member vertically and laterally slidably supported within said guide bracket and resting on and supported by the flange of said wheel, the reservoir member having limited vertical rocking movement in the plane of the wheel with respect to the guide bracket, and means engaging the reservoir member and adapted to engage said stationary frame element for limiting said rocking movement, and lubricating means within the reservoir.

3. The combination of a wheel having a flanged tread, a stationary support spaced from the wheel, a vertical guide bracket carried by said support, a reservoir member resting upon and supported by the wheel

flange, means within the reservoir for lubricating the flange, means mounted at one side of the reservoir slidably engaging the guide bracket for permitting vertical movement of the reservoir, said means constituting a support permitting lateral movement of the reservoir member, and means engaging the other side of the reservoir member and engageable with said stationary support for limiting rocking movement of the reservoir member in the plane of the wheel.

4. In a device for lubricating a car wheel flange, a stationarily mounted U-shaped bracket provided in its arms with vertically elongated slots, a reservoir member resting on and supported by the wheel flange, lubricating means within the reservoir member, spaced ears at one side of the reservoir member, a securing member passing through said slots and said ears and movable along the former, the reservoir member being of less width than the space within the bracket so as to have lateral movement with respect thereto, ears at the opposite side of the reservoir member, and means engaged through said ears and engageable with a portion of the car frame for limiting vertical rocking movement of the reservoir member.

5. In a device for lubricating the flange of a locomotive or car wheel, a stationary guide bracket, a reservoir member, means within the reservoir for supplying lubricant to the wheel flange, the reservoir member resting upon and being supported by the flange of the wheel, means pivoted to one side of the reservoir member and vertically slidably mounted along the guide bracket for permitting vertical movement of the reservoir member, and means connected with the reservoir member at the opposite side thereof for limiting rocking movement of the reservoir member in the plane of the wheel with respect to the guide bracket.

6. In a car or locomotive wheel flange lubricator, a supporting bracket mounted upon a portion of the car or locomotive frame, an inverted U-shaped bracket secured to said supporting bracket and having its arms provided with vertically extending alining slots, a reservoir member located at the front of said second named bracket and having ears extending between the arms thereof, a securing element passing through said ears and said slot, said reservoir member resting upon the wheel flange and being supported thereby, said slots permitting vertical movement of the reservoir member to accommodate movements of the wheel with respect to the frame, other ears at the front side of the reservoir member, and an arm extending through said second named ears and extending beneath the frame in normal spaced relation thereto, said arm being engageable with the frame to limit rocking movement of the reservoir member.

7. The combination of a wheel having a flanged tread, a lubricator resting on and supported by the flange of said wheel, said lubricator consisting of a reservoir and means for conveying a lubricant from said reservoir to the flange of said wheel, means for guiding said lubricator in a vertical plane and in a transverse plane, additional means limiting the revolving of said lubricator in a vertical plane.

8. The combination of a wheel having a flanged tread, a lubricator comprising a stationary guide bracket, a lubricant reservoir member mounted for vertical and lateral sliding movement within the guide and resting on and supported by the flange of said

wheel, said reservoir member having limited rocking movement in the plane of the wheel.

9. In a wheel flange lubricator, a support, a reservoir member resting upon and supported by the flange of the wheel to be lubricated, means within the reservoir member for conducting lubricant to the flange of the wheel, and means extending transversely with respect to the wheel and connecting the reservoir member with the support to permit the reservoir member to have vertical sliding movement, lateral sliding movement transversely of the wheel tread and limited vertical rocking movement in a plane at right angles to the wheel axis.

ROBERT L. BLACK.
